UNITED STATES PATENT OFFICE.

EUGÈNE G. CONRADSON AND ALBIN FORSELL, OF BROOKLYN, NEW YORK.

IMPROVEMENT IN SPONGE-HOLDERS.

Specification forming part of Letters Patent No. **158,573**, dated January 12, 1875; application filed April 17, 1874.

To all whom it may concern:

Be it known that we, EUGÈNE GOTTFRID CONRADSON and ALBIN FORSELL, both of the city of Brooklyn, Kings county, State of New York, have invented certain Improvements in Sponge-Holders, of which the following is a specification:

The object of our invention is to provide for a cheap, strong, and convenient sponge-holder, by aid of which a sponge is held securely to a metallic holder, which again is fastened to a wooden handle of sufficient length to reach windows, walls, ceilings, &c., which are required to be cleaned.

Our invention consists in constructing a straight or bent stem, provided on the upper part with three forks, extending from the stem at equal distances apart, perpendicular to the stem, and terminating at the ends in prongs bent downward at right angles to the forks.

The stem is made pointed at the other end for the purpose of piercing the sponge, which is pressed up against the forks, the prongs penetrating into the sponge, and preventing the same from being twisted or turned. A circular sleeve, with a hole in the center fitting the stem, is then slipped over the pointed

end, and pressed against the sponge, and held in this position by aid of a set-screw applied to the side of the sleeve-holder.

In order to describe more fully our invention, we refer to the accompanying drawing forming a part of this specification.

Figure I is a side view of our improved sponge-holder. Fig. II is a plan view of the same.

A is the stem, with point *b*, and with the three forks *c c c*, with prongs *d d d* at the opposite end. D is the sleeve, with sleeve-holder *e*, in the side of which the set-screw *g* is inserted. H is the sponge. I is the wooden handle.

Having thus described our invention, we desire to claim—

In combination with stem A, provided with forks *c* and prongs *d* and handle I, the sleeve D, holder *e*, and set-screw *g*, substantially as and for the purpose set forth.

EUGÈNE GOTTFRID CONRADSON.
ALBIN FORSELL.
